CLAIM

The ornamental design for monitor, as shown and described.

DESCRIPTION

FIG. 1 is a perspective view of monitor showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view of the design; and,

FIG. 9 is the same view as FIG. 4, but showing that a display panel of the monitor is lowered.
